UNITED STATES PATENT OFFICE.

WILLIAM EDWARD BIEBOW, OF LOS ANGELES, CALIFORNIA.

HYDROMETER.

1,405,094.

Specification of Letters Patent. Patented Jan. 31, 1922.

Application filed February 2, 1921. Serial No. 441,885.

To all whom it may concern:

Be it known that I, WILLIAM EDWARD BIEBOW, a citizen of the United States, and a resident of Los Angeles, in the county of 5 Los Angeles and State of California, have invented certain new and useful Improvements in Hydrometers, of which the following is a specification.

The present invention relates in general 10 to hydrometers, and more particularly to an improved hydrometer especially adapted for use in testing storage batteries of automobiles.

The object of the invention is to provide 15 an improved hydrometer of this character which is of simple and durable construction, reliable in operation, and easy and inexpensive to manufacture, which is adapted and protected to withstand the rough usage 20 incident to its employment in garages and with automobiles, which is a non-conductor, and which will not be impaired or rendered inaccurate by virtue of variations in temperature, and which is always available and 25 effective to accurately and easily test the storage batteries of automobiles.

Other objects and advantages reside in the certain novel features of the construction, arrangement and combination of parts, 30 which will be hereinafter more fully described and particularly pointed out in the appended claims, reference being had to the accompanying drawings forming a part of this specification, and in which:

35 Figure 1 is a side elevational view of the invention,

Figure 2 is a longitudinal sectional view therethrough,

40 Figure 3 is a transverse sectional view on the line 3—3 of Figure 2,

Figure 4 is a similar view on the line 4—4 of Figure 2,

Figure 5 is a similar view on the line 5—5 of Figure 2.

45 Referring to the drawings wherein for the sake of illustration is shown a preferred embodiment of the invention, the numeral 10 designates a tubular receptacle of transparent material preferably of high test 50 boiler tubing Scotch glass. The receptacle 10 is adapted to operatively receive a hy-

drometer 11 having an elongated and graduated stem 12 which is slidably received in the guide opening 13 of a guide 14, which as clearly shown in Figure 4, embodies a 55 central guide block 15 and spider arms 16 connecting the block to the tubular receptacle.

Plugs 20 and 21 close the opposite ends of the tubular receptacle and are constituted of 60 soft rubber or similar material. Each plug is provided with an annular flange, designated at 22 and 23, respectively, and which abut the adjacent end of the tubular receptacle. Each plug is further provided 65 with an axial bore indicated at 24 and 25 respectively. A set of spaced triangular plates of fibre is arranged adjacent each plug, these sets including plates 26, 27, 28 and 29, and the plate 27 of one set and the 70 plate 29 of the other set bearing against the adjacent plug. Between the plates 26 and 27 of one set a triangular plate 30 of elastic or cushioning rubber is arranged, and a similar plate designated at 31 is arranged be- 75 tween the plates 28 and 29. These plates 30 and 31 project or extend beyond the sets of plates and the other elements of the instrument are shown in the drawing. The plates 26, 27 and 30 and the plates 28, 29 and 31 80 are provided with a plurality of alined openings and with axial bores communicating with the axial bores of the adjacent plug. Rods 33 of fibre extend between and through the alined openings of the plates 85 and parallel and adjacent the exterior of the tubular receptacle. Preferably there are three of these rods and they are arranged at the corners of the triangular plates as clearly shown in Figures 3 and 5. The ends of 90 the rods are threaded and receive fibre nuts 34 which abut the outermost plate on each set and serve to maintain the parts assembled and to tension the cushioning ele- 95 ments or cushioning plates 30 and 31.

Bushings 35 and 36 having axial ducts 37 and 38 extending therethrough and terminating in branches 37^a and 38^a are inserted in the axial bores as clearly shown in Figure 2, and are adapted for connection 100 to a bulb 40 and a flexible hose 41. By providing the axial ducts 38 with the branches

38^a the possibility of the base or lower end of the hydrometer interfering with the inlet or discharge of the liquid to be tested is precluded for the point or area of contact 5 of this lower end is usually entirely accommodated by the space between the branches so that neither branch is in any way obstructed, but in any event this point or area of contact is not sufficient to extend across 10 both branches.

In practice, the hydrometer may be utilized in garages and similar places for testing the storage batteries of automobiles, and it is well adapted to withstand the stresses 15 incident to this hard usage. In the first place, the cushioning elements 31 which are tensioned by taking up the nuts 34 on the fibre rods are always exerting a cushioning action and tend to take up or absorb the 20 shocks incident to impacts or the like, and thus to relieve the hydrometer 11 or the other delicate parts of the instrument from the action of deleterious stresses. The fibre rods transmit the cushioning action of the 25 plates 30 and 31 and further they protect the tubular receptacle for they lie at regular intervals about the exterior thereof. Finally the plates being of triangular shape, permit of the hydrometer being placed on a 30 smooth surface with safety as it prevents rolling of the hydrometer and precludes to a large extent falling and damaging thereof. It is to be noted however that with this 35 construction, the hydrometer is well adapted to withstand the action of falls and the like, for the cushioning elements project beyond the other plates and are most likely to receive the force of impact and even should they not receive this force of impact, the 40 fibre rods or the fibre plates will receive it, and these are so organized with the cushioning elements that the stresses set up therein are absorbed or taken up by these cushioning elements.

45 If desired the elements of the instrument with the exception of the transparent receptacle, the guide, and the cushioning elements, may be made of hard rubber, whereby the instrument is absolutely acid-proof. The 50 guide however is preferably constructed of ivory, and does not expand and contract.

I claim:

1. In an instrument of the character described, a tubular receptacle of transparent material, a hydrometer operatively arranged 55 therein, a guide for said hydrometer within said receptacle, a plug of hard rubber closing each end of said receptacle, each plug having an annular flange abutting the end of 60 the tube and being provided with an axial bore, a set of spaced triangular plates of fibre adjacent each plate, one plate of each set bearing against the adjacent plug, a triangular plate of cushioning rubber inter-

posed between the spaced plates of each set, 65 said spaced plates and said plates of rubber being provided with alined openings, and with axial bores communicating with the axial bores of said plug, a plurality of rods extending between said plates and through 70 the openings thereof, nuts threaded upon the ends of the rods and abutting the outermost of said plates, and bushings inserted in said axial bores and adapted for connection with a bulb and a flexible hose respectively. 75

2. In an instrument of the character described, a tubular receptacle of transparent material, a hydrometer operatively arranged therein, a plug of hard rubber closing each 80 end of said receptacle, each plug having an annular flange abutting the end of the tube and being provided with an axial bore, a set of spaced triangular plates of fibre adjacent each plate, one plate of each set bearing 85 against the adjacent plug, a triangular plate of cushioning rubber interposed between the spaced plates of each set, said spaced plates and said plates of rubber being provided with alined openings, and with axial bores communicating with the axial bores of said plug, a plurality of rods extending between 90 said plates and through the openings thereof, nuts threaded upon the end of the rod and abutting the outermost of said plates, and bushings inserted in said axial bores 95 and adapted for connection with a bulb and a flexible hose respectively.

3. In an instrument of the character described, a tubular receptacle of transparent material, a hydrometer operatively arranged 100 therein, plugs for the end of said tubular receptacle, each plug having an annular flange abutting the end of the tube, a set of spaced plates adjacent each plug, a plate of cushioning material interposed between the spaced 105 plates of each set and projecting beyond the same, said spaced plates and said plates of rubber being provided with alined openings, a plurality of rods extending between said plates and through the openings thereof, and nuts threaded on the ends of the rods and 110 abutting the outermost of said plates.

4. In an instrument of the character described, a receptacle of transparent material, a hydrometer operatively arranged therein, 115 plugs for the ends of said receptacle, a set of spaced plates of fibre adjacent each plug, a plate of cushioning material interposed between the spaced plates of each set and projecting beyond the same, and a plurality of 120 rods extending between and secured to said plates.

5. In an instrument of the character described, a tubular receptacle of transparent material, a hydrometer operatively arranged 125 therein, means for closing the ends of the tubular receptacle, a set of plates adjacent each of said end closing means, a cushioning

element arranged between the plates of each set, and rods extending between and secured to said plates and said cushioning elements, all as and for the purpose set forth.

- 5 6. In an instrument of the character specified, a receptacle of transparent material, a hydrometer operatively arranged therein,

spaced plates adjacent each end of the receptacle, a cushioning element between said spaced plates, and fibre rods extending between and secured to said spaced plates and said cushioning elements.

WILLIAM EDWARD BIEBOW.
